UNITED STATES PATENT OFFICE.

WILLIAM B. LA MASTERS, OF SAN MARCIAL, NEW MEXICO.

COMBINED FOLDING IRONING-BOARD AND STEP-LADDER.

1,101,294.

Specification of Letters Patent.

Patented June 23, 1914.

Application filed December 31, 1913. Serial No. 809,687.

To all whom it may concern:

Be it known that I, WILLIAM B. LA MASTERS, a citizen of the United States, residing at San Marcial, in the county of Socorro and 5 State of New Mexico, have invented new and useful Improvements in Combined Folding Ironing-Boards and Step-Ladders, of which the following is a specification.

The present invention relates to a combined folding ironing board and step ladder and resides in the construction, combination and arrangement of parts set forth in the following specification and falling within the scope of the appended claims.

15 In the drawings: Figure 1 is a perspective view showing the device set up as an ironing board, Fig. 2 is a similar view showing the device in the form of a step ladder, the supporting legs for the ironing board being folded against the sides of the ladder, Fig. 3 is a detail view illustrating the frame spread outwardly of the ladder to provide a support for articles which may be used by the person upon the ladder, Fig. 4 is a 20 central transverse sectional view through the device with the frame in the position illustrated in Fig. 3, Fig. 5 is a detail plan view looking toward the inner face of the lower end of the board, showing the manner in which the sleeve board sustains the combination foot and brace member, and Fig. 6 is a detail sectional view through the end of the device when set up as an ironing board, and illustrating the manner whereby the 25 sleeve board prevents an upward movement of the ironing board.

Referring now to the drawings in detail, the ladder is indicated by the numeral 1, and may be, and preferably is, of the usual 40 construction of ordinary step ladders, including the side stiles 2 and connecting steps 3. The stiles, in the upper ends thereof have each secured thereto a bracket 4 which has its upper portion provided with an inturned 45 flange, and each of the said brackets extends a suitable distance beyond the inner edges of the stiles, while connected with the said brackets is the top member or platform 5 for the ladder.

50 The ironing board is designated by the numeral 6, and is of a width approximately equaling that of the ladder, but is preferably of a length slightly less than the stiles of the ladder. One end of the board is 55 rounded, and is provided upon what may be termed its lower face with a transversely

arranged bar or cleat 7, which is secured to the end of the board in any desired or preferred manner, and connected with the sides as well as with the ends of the cleat are substantially L-shaped metallic plates 8. The cleats are each provided with an opening which is adapted to register with a similar opening in the side members of each of the brackets 4, the said openings being provided for the reception of pivot members 9. The inner face of the board 6 and one of the steps of the ladder are provided with eyes to receive the opposite ends of a flexible member 10, which is preferably in the nature of a chain and which serves as a means for limiting the spreading of the ladder from the board. The step, to which the flexible member 10 is connected has its underface provided with transversely arranged blocks 75 which are also secured to the sides of the ladder, and the said blocks have their lower and inner corners notched, as at 12.

The free end of the board is rounded, and its side edges are preferably inclined or of an arcuate formation to their juncture with the said rounded end. The board, at a suitable distance away from its end, is provided adjacent its opposite edges with bearings 13 within which is journaled the upper arm 14 of a combined foot and spacing member. This member is preferably constructed from a piece of heavy metal of tubiform formation, and the side arms 15 thereof have their lower portions curved outwardly and terminating in inwardly curved feet 16, the rounded ends of the feet being continued inwardly to a lower connecting portion 17, and this portion, when the device is in the position illustrated in Fig. 1, is 95 adapted to underlie a plate 18 which is arranged centrally of the board 6. The board, below the plate is provided with a substantially U-shaped keeper 19, and the said board above the arm 14 of the combined foot and spacing member is provided with a metallic clip 20, the said clip adapted to receive the upper and enlarged portion of a sleeve board 21, while the opposite and reduced end of the board is passed through 100 the keeper 19, so that the upper and lower transverse arms 14 and 17 of the combined foot and spacing members are effectively retained in proper position upon the board to receive the weight upon the ladder. It 110 will be noted that the feet 16 are disposed a suitable distance below the rounded end of

the board. In addition to the cleats 7, the board may be provided with a second transverse cleat 23, but the said cleat is of a lesser thickness than that of the cleat 7, and is 5 adapted to serve as a bearing plate for the sleeve board when the same is arranged as just described.

When the device is employed as an ironing board, the sleeve board 21 is removed, and 10 the combined foot and spacing member is swung until its feet 16 are received within the notches 12 of the blocks 11. In order to sustain the ironing board in a horizontal position, I have pivotally secured to the 15 brackets 4 the legs 24 of a frame 25. The frame is provided with one or a number of connecting bars 26 and each of the legs has pivotally connected therewith a link 27 which is adapted to co-act with a similar 20 link 28 provided upon the stiles of the ladder, and these links 27 and 28 are in turn pivotally connected to provide a carriage joint 29. It will be noted that the links must be swung inwardly before the said 25 links and frame can be folded against the ladder, and as a consequence I have found it desirable, in some instances, to sustain the frame 25 in the position just described, when the device is employed as a step ladder, the 30 legs as well as the connecting bar or bars of the frame providing effective means for sustaining articles thereon so that the same will be within ready reach of the person upon the ladder.

35 The platform 5 projects a suitable distance beyond the face of the said board, and the projecting portion is provided with an elongated opening 30, the lower wall of which is flush with that of the outer or 40 working face of the board, and the board 21 is provided with a substantially L-shaped bracket 22, the lower and horizontal member of which is adapted to pass through the 45 opening 30 so that the same will contact with the face of the ironing board, and prevent an upward swinging movement of the said board, and so retain the feet of the spacing member within the notches 12 of the blocks 11.

50 From the above description, taken in connection with the accompanying drawings, the simplicity of the device as well as the advantages thereof will, it is thought, be perfectly apparent to those skilled in the art 55 to which such inventions appertain without further detailed description.

Having thus described the invention, what I claim is:

60 1. In a device of the class set forth, a ladder including a platform, a board pivotally secured beneath the platform, a combined foot and spacing member journaled upon

the board, said member being constructed of a metal tube and comprising parallel side arms which extend from its journal and 65 which have their free ends curved outwardly and terminating in inturned portions forming the feet of the member, the said feet adapted to engage between the stiles of the ladder to space the board from the ladder 70 and to extend beyond the end of the ladder when the said member is folded upon the said board, means, including a removable member, for sustaining the combined foot and spacing member against the board, and 75 spring means for retaining the removable member in engagement with the combined foot and spacing member.

2. In a device for the purpose set forth, a ladder having brackets at the upper ends of 80 its stiles, a platform secured to the brackets, an ironing board pivotally connected with the brackets, a flexible element between the board and ladder to limit the swinging movement of the said board and ladder, a 85 combined support and foot member journaled in bearings upon the ironing board and adapted to project below the foot board, an auxiliary board removably connected with the ironing board and adapted to contact with the combined support and foot member to sustain the same longitudinally 90 of the board.

3. In a device for the purpose set forth, a ladder having its stiles, at one of its ends 95 provided with brackets, a platform secured to the brackets, a frame connected with the said upper end of the ladder, said frame comprising a pair of connected leg members and a pair of jointed stop links providing 100 supports for the leg members, an ironing board pivotally connected with the brackets, means for limiting the swinging movement of the board away from the ladder, a combined support and foot member journaled in 105 bearings upon the inner face of the board and adapted to extend beyond the board when the device is set up as a ladder, a supporting plate for the support and foot member, a keeper plate upon the board, a metallic 110 clip upon the board, a sleeve board having a reduced end adapted to be engaged by the clip and keeper and to bear against the support and foot member, and the stiles of the ladder having notched blocks which are 115 adapted to receive the foot portions of the combined support and foot member when the device is set up as an ironing board.

In testimony whereof I affix my signature in presence of two witnesses.

WILLIAM B. LA MASTERS.
